United States Patent Office

Des. 194,631
Patented Feb. 19, 1963

194,631

JUG

Clara Virginia Eicholtz, Midland, Mich., assignor to The Dow Chemical Company, Midland, Mich., a corporation of Delaware

Filed July 5, 1962, Ser. No. 70,810

Term of patent 14 years

(Cl. D58—5)

Fig. 2

Fig. 5

Fig. 4

Fig. 3

Fig. 1

FIGURE 1 is an elevational view of a jug showing my new design;

FIGURE 2 is a top plan view thereof;

FIGURE 3 is a perspective view thereof;

FIGURE 4 is an enlarged fragmentary elevational view of an upper portion thereof; and

FIGURE 5 is an enlarged fragmentary elevational view of a lower portion thereof.

I claim:

The ornamental design for a jug, as shown.
